(57) CLAIM

I claim the ornamental design for a display window with level of service graphical user interface, as shown and described.

DESCRIPTION

FIG. 1 is a first front view of a first embodiment of a display window with level of service graphical user interface providing an indicator of a level of service for presentation on a display screen of a computing and/or communications device;

FIG. 2 is a second front view of the first embodiment of the display window with level of service graphical user interface of FIG. 1;

FIG. 3 is a third front view of the first embodiment of the display window with level of service graphical user interface of FIG. 1;

FIG. 4 is a fourth front view of the first embodiment of the display window with level of service graphical user interface of FIG. 1;

FIG. 5 is a fifth front view of the first embodiment of the display window with level of service graphical user interface of FIG. 1;

FIG. 6 is a sixth front view of the first embodiment of the display window with level of service graphical user interface of FIG. 1;

FIG. 7 is a first front view of a second embodiment of a display window with level of service graphical user interface providing an indicator of a level of service for presentation on a display screen of a computing and/or communications device;

FIG. 8 is a second front view of the second embodiment of the display window with level of service graphical user interface of FIG. 7;

FIG. 9 is a third front view of the second embodiment of the display window with level of service graphical user interface of FIG. 7;

FIG. 10 is a fourth front view of the second embodiment of the display window with level of service graphical user interface of FIG. 7; and,

FIG. 11 is a fifth front view of the second embodiment of the display window with level of service graphical user interface of FIG. 7.

The broken lines used for text, icons, and the display window with level of service graphical user interface in FIGS. 1-11 are for illustrative purposes only and form no part of the claimed design.
